JOHN GEORGE LEYNER, OF DENVER, COLORADO.

PNEUMATIC FEEDING DEVICE FOR STOPING-DRILLS.

1,065,059:

Specification of Letters Patent.

Patented June 17, 1913.

Application filed October 23, 1911. Serial No. 656,267.

To all whom it may concern:

Be it known that I, JOHN GEORGE LEYNER, a citizen of the United States of America, residing in the city and county of Denver 5 and State of Colorado, have invented a new and useful Pneumatic Feeding Device for Rock-Drilling Stoping-Drills, of which the following is a specification.

My invention relates to improvements in 10 pneumatic feeding device for rock drilling stoping drills, and the objects of my invention are:

First—To provide a pneumatic feeding device for stoping drills, in which a single 15 manually operated valve is rotatably mounted in the stoping drill and is provided with a handle that is adapted to be moved reciprocally through the arc of a circle during the operative movement of the valve, and 20 that is arranged in such coöperative relation to a series of air inlet and exhaust ports formed in the stoping drill that when said handle and valve are moved a part of their operative movement, the valve will admit the actuating fluid to the drill bit feeding piston first, and when moved the rest of its operative movement, will admit the actuating fluid to the drill bit's driving piston afterward, and is so arranged that when the 25 actuating fluid is first turned into the drill bit feeding part of the stoping drill, it remains turned therein until and during all of the time the actuating fluid is turned into the drill driving part of the stoping drill, 30 and is also so arranged that when the actuating fluid is to be shut off from the stoping drill, the handle and valve are first moved backward and the actuating fluid is first turned off from the drill bit driving 35 part of the stoping drill, and then from the drill bit feeding part of the stoping drill afterward, and when moved to its initial 40 position of disuse, opens the drill bit feeding part of the stoping drill to the atmosphere.

Second—To provide an air-feeding device 45 for stoping drills having a cup shaped piston head upon which the feeding tube is slidably mounted and that receives the air 50 pressure between its cupped end and the adjacent rear cylinder head of the drilling engine's cylinder, and in which the piston head and its abutment engaging piston rod is stationary, and its surrounding tube feeds

forward with the drill bit and the cylinder 55 of the drilling engine; and

Third—To provide a simple feeding device for stoping drills that is so coöperatively arranged and connected to the cylinder of the stoping drill that it will resili- 60 ently yield under severe strains, sudden shock and severe falls that would tend to break their connecting parts if rigidly secured together.

I attain these objects by the mechanism 65 illustrated in the accompanying drawings, in which:

Figure 1 is a vertical, longitudinal, sectional view of the improved stoping drill, Fig. 2 is a plan view of the air feed tube 70 showing the back head and drill rotating handle carried thereby, at the forward end of the same, and the piston rod guide cap on its rear end, Fig. 3 is an end view of the back head, Fig. 4 is a vertical, transverse 75 sectional view of the same, Fig. 5 is an end view of the piston rod guide cap, Fig. 6 is an end view of the rear cylinder head, Fig. 7 is a vertical sectional view of the same, Fig. 8 is an end view of the piston 80 head, Fig. 9 is a side view of the same, Fig. 10 is a plan view of a portion of the air feeding device and of the members that coöperatively connect it to the cylinder portion of the rock drilling engine, Fig. 11 is 85 a horizontal, sectional view of the hammer piston cylinder casing on the axial plane of the throttle valve, the said valve being shown in full lines, Fig. 12 is a horizontal, sectional view through the valve chest of the cylinder casing, the valve and end plugs being omitted, Fig. 13 is a vertical, transverse, 90 sectional view thereof on the line 13—13 of Fig. 12, Fig. 14 is a side view of the throttle valve, Fig. 15 is a view of the opposite 95 side of the said valve, Fig. 16 is a vertical, longitudinal, sectional view through the ported portion of the said valve, Fig. 17 is a transverse, sectional view thereof, Fig. 18 is a sectional view similar to Fig. 11, but 100 on a slightly reduced scale and showing a portion only of the cylinder, the throttle valve being in a position reverse to that shown in Fig. 11, Fig. 19 is a transverse, sectional view through the throttle valve, and a 105 portion of the cylinder, the valve being in the same position shown in Fig. 18, or so as to cut off the pressure supply from the cylinder.

and feed tube and exhaust the air from the said tube, the three positions of the valve being indicated by dotted lines, and Fig. 20 is a view similar to Fig. 19, showing the valve 5 in such a position as to admit air to the feed-tube, before its admission to the main cylinder.

Similar letters of reference refer to similar parts throughout the several views.

- 10 Referring to the drawings, the numeral 1 designates the cylinder portion of the casing of my improved stoping drill, in which a hammer piston 2 is reciprocally mounted. 3 designates the front cylinder head, 15 which is provided with a hub portion 4, that fits snugly but loosely into the cylindrical bore 5 of the cylindrical casing 1. The front cylinder head is provided with a striking pin 6 which is mounted to move reciprocally a short distance. One end projects into the axial bore of the cylinder 1 and into the reciprocal path of the hammer piston 2 far enough to be driven forward by the hammer piston on its reciprocal strokes 20 against the end of the drill bit 7, and is adapted to have a short forward and rearward feeding movement of about a half of an inch to compensate for the automatic feeding movement of the stoping drill. 25 The reciprocal movement of the drill bit striking end of the striking pin is defined by the adjacent end of a drill bit supporting sleeve 9, which I term the drill bit holding chuck, which is provided with a hub portion 30 that fits into the larger bore of the front cylinder head. This drill bit supporting sleeve 35 is provided with an axial aperture that is adapted to support the shank end of the rock crushing drill bit 7. 40 The front head 3 is provided with oppositely extending air vent apertures 18, which are preferably positioned at the top and bottom sides of the same, and are adapted to permit any air that may leak from the cylinder past the striking pin into the aperture in the head, from cushioning the striking pin, thus preventing its striking the drill bit with the full force of the blow of the hammer piston. 45 The hammer piston is a cylindrical piston, with flat ends and preferably without piston rings. Its reciprocal movement is defined by the striking pin supporting front cylinder head, and a rear cylinder head 14, 50 which fits against the rear end of the cylinder, and is provided with a hub portion 15 that projects into it a short distance. This rear cylinder head is also provided with a rearwardly projecting hub extension 15^A, 55 which is formed into two reduced step portions 16 and 17, as shown in Figs. 1 and 7. The step portion 16 is arranged to receive the forward end of an air feed tube 18, which fits snugly but loosely over it, and the step 60 portion 17 is of smaller diameter and is provided

with a collar end portion 19. The step 17 is adapted to receive and retain between its collar 19 and its adjacent step portion 16, an air feed retaining ring 20, which is a split expansive steel ring that is sprung over the collar portion 19 and fits within an axial recess 21, formed in the front end of the piston head 22 of the air feed tube 18. This piston head 22 is a plug shaped circular piston head which is provided with a threaded axial aperture 23, in which a reduced threaded end portion on the inner end of a piston rod 24 is screwed. A washer 25 of metal or other rigid material is placed on the reduced threaded end of the piston rod against the shoulder 26 formed between the threaded portion and the body of the piston rod, and the adjacent end of the piston head is provided with a reduced step portion 28, around which a resiliently expanding steel ring 28^A is placed, and over this spring ring 28^A the circumferential band portion of a cup shaped washer 29 of leather or other suitable material is placed. The body portion of this cupped washer is mounted on the reduced end 30 of the piston head between the metal washer and the adjacent shoulder of the piston head. The expanding ring 28^A acts to press the leather washer against the circular wall of the piston bore 95 of the air feed tube. The front end portion of the air feed tube extends into and is secured to a sleeve 31, preferably by being expanded therein, which sleeve I term the back head of the stoping drill. This back 100 head bears against the rear cylinder head, and on its opposite side projecting lug portions 33 are formed, and the front cylinder head, the drill bit supporting chuck and the cylinder casing are also provided on their 105 opposite side portions with lug portions 34, which are also arranged in alignment with the lugs of the back head. The lugs of these parts are all provided with apertures 35, which are adapted to receive bolt rods 36. These bolt rods 36 extend loosely through the apertures in the lugs and are provided with heads 27 that fit against the outside of the lugs of the chuck. The opposite ends of these bolt rods extend through 110 and beyond the lugs on the back cylinder head and through the apertured ends of a washer plate 39, which is mounted loosely on the feed tube 18, and coil springs 40 are interposed between the plate 39 and the 115 back head 31. The ends of the rods are threaded to receive nuts 41. The coiled springs are adapted to be compressed by screwing the nuts 41 against the washer plate, and the tension under which the 120 springs are thereby held causes them to exert an outward pull on the rods and also a pressure upon the back head which clamps the cylinder, its head portions and the chuck together in alignment and with a resilient 125 130

pressure that permits each piece of all of them together to yield under torsional or twisting strains, or sudden jars, thus preventing breakage or disarrangement of the said parts and their interior coöperating members. In order to secure the nuts 41 of these bolts against accidental movement that would relieve the springs of their adjusted tension, I provide their washer engaging faces with transversely arranged ribs or keys 42, which are adapted to be engaged by grooves 43 in the adjacent face of the washer plate, into which grooves the keys slip as the nuts are turned on the rod against the plate, the nuts being finally stopped with their keys resting in the groove of the plate when the springs are compressed to the required tension to clamp the cylinder and its heads and the chuck together.

10 The back head 31 is provided with a projecting hub portion 44, through one side of which a slot 45 is formed along the opposite edges of which two lugs 46 are formed, through which a bolt 47 is extended, and is adapted to clamp the lugs and the sides of the hub together around one end of a hand operated lever 48, which is preferably partially threaded or is otherwise removably secured to it, and is arranged to be clamped 15 tightly in it against accidental movement or displacement. The opposite end of this lever is turned at right angles to its length to form a handle that can be grasped by an operator easily and quickly in any position in which the stoping drill is placed. This handle is employed by an attendant to oscillate the stoping drill when in operation, as it is necessary that the drill bit be turned or moved or partially rotated in alternate directions while drilling rock, as will be described more fully hereinafter. The air feed tube extends rearwardly from the back head and may be made of any predetermined length that will enable the stoping drill to 20 be easily and quickly handled. I preferably make this air feed tube about thirty inches long and its outer end is threaded and is adapted to receive a cap 49 through which the piston rod extends. This cap comprises 25 a cylindrical portion, which fits over the end of the air feed tube and a hub portion through which the piston rod 24 passes. The interior of the cylindrical portion is threaded adjacent to the hub end thereof to receive the threaded end of the air feed tube. This cylindrical portion is slotted and apertured lugs 50 are formed on opposite walls of the slot, which receive a clamping bolt 51 by which the cap may be clamped upon 30 the end of the tube against accidental displacement. The hub of the cap at its junction with the cylindrical portion is formed with a hexagonal wrench receiving portion 49^A, as shown in Fig. 2. This piston rod 24 I term an abutment engaging piston rod, as

it is adapted to be held stationary against any part of the side walls or of the floor or roof of the stope portions of mines, or against any suitable stationary block or other object that is made to act as an abutment for it, as will be more fully explained 35 hereinafter.

5 A small air vent aperture 52 is formed through the shell of the air feed tube, which is adapted to allow the air in the tube behind the piston to escape as the piston moves forward, and this aperture also permits the actuating air to exhaust when the piston reaches the limit of its outward movement.

10 The piston rod extends from the piston head of the air feed tube through and beyond the end of the air feed tube a short distance, and its terminal end is tapered to a point, as shown.

15 The drill bit driving hammer piston 2 in the cylinder 1 is operated by a valve that is inclosed in a valve chest 56, which forms a part of and is preferably cast integral with it. This valve chest has a cylindrical bore 57, formed through it, which forms a valve seat for a stem and collar form of valve 58, which fits snugly but reciprocally in the said bore. The opposite end portions of this bore are threaded and plugs 59 are threaded to 20 them. The outside ends of the plugs are provided with head portions that screw up against the ends of the valve chest, and these head portions are provided with surfaces adapted to receive a wrench for inserting the 25 plugs into and for removing them from the valve chest. The valve comprises a stem portion having collar portions 61 and 62 at its opposite ends, and two collar portions 63 and 64 intermediate of its ends at predetermined equal distances from its ends and from the center of its length, said collars being arranged to cover two cylinder inlet ports 65 and 66 and to control two exhaust ports 67 and 68. The cylinder inlet ports 30 65 and 66 extend from the valve seat to the opposite ends of the hammer piston cylinder, while the exhaust ports 67 and 68 extend from the valve seat into an exhaust outlet aperture 69 formed in and along the top of 35 the valve chest that opens to the atmosphere at the rear end of the valve chest. The air inlet ports are placed at each side of the center of the length of the valve seat, and are controlled by the inside collars of the 40 valve, and centrally between them an annular entrance port 70 is formed, which port communicates with a conical valve seat 71, which forms a continuation of an air inlet port 72, which is formed in a hub 73 cast on 45 one side of the cylinder casing. The entrance to this air inlet hub 73 is threaded and a bushing 74 is threaded in it, which is provided with an inwardly flaring tapering aperture in which the tapering end portion 50

of an elbow 75 fits, the outer end of which is threaded to receive a hose coupling nipple 76. The valve seat 71 is provided with a throttle valve 77, which may consist of any suitable form of air controlling valve, but I preferably, however, use a valve having a tapered tubular portion which is seated in the tapered or conical seat 71, and which is provided with a port 78, which is adapted to register with the entrance port 70 in the cylindrical valve seat 57, a ground joint being formed between this tapering tubular valve and its tapering seat. The stem of the valve extends through a hub on the opposite side of the casing, and a handle 79 is secured to its projecting end, preferably by being bolted thereto by a bolt 80.

A small air port 81 is drilled horizontally into the valve chest from the outside, and has its outer end closed by a plug. This port communicates with the tapered valve seat 71, so as to be controlled by the tubular throttle valve, and it is intersected by a substantially vertically drilled port 82, the entrance of which is also closed by a plug, and this port 82 also intersects the inner end of a horizontal port 83, that is drilled into the end portion of the valve chest. This port 83 communicates with an annular groove 84, that is formed in the inner face of the rear cylinder head, which groove forms a distributing port from which extend a plurality of obliquely arranged ports 85, which communicate with an axial chamber 86 in the rearwardly extending hub portion of the rear cylinder head, from which chamber the air acts directly on the piston head 22 of the piston rod 24 of the air feed tube 18, and pushes the feed tube and the drilling cylinder forward on the piston head until the drill bit bears against the rock in operative position to drill a hole, when the air under constant pressure against the piston head holds the entire stopping drill suspended between the point of its abutment piston rod and the point of the drill bit, in operative rock-drilling position.

The port 78 in the throttle valve communicates with an axial port 78^a in the body of the valve, and the port 78^a communicates with the inlet port 72. A port 78^b is formed in the periphery of the throttle valve and extends from one side of the port 78 substantially a fourth of the way around the periphery of the valve. This port is adapted to communicate with the port 81 when the valve is turned in the position shown in Figs. 1 and 11, so that air may pass from the port 78 to the port 78^b and thence through cylinder ports 81, 82 and 83 and ports 84 and 85 in the rear cylinder head to the cylinder-head chamber 86, whence it acts directly against the adjacent end of the piston head 22. A slight groove or port 78^c

is cut in the edge of the port 78 opposite the port 78^b. The object of this port 78^c is to admit air through the ports 81, 82, 83, 84 and 85 to the interior of the air feed tube 18 when the valve is turned to cause the port 78^c to register with the port 81, which position is assumed by the valve when the handle is turned in a vertical position, in order that it may act on the feed piston 22, and the admittance of air from the valve through the port 81 into the feed tube starts the feed tube forward on the piston head and feeds the drill bit against the rock. This is done before air is admitted to the hammer piston, and consequently before the hammer piston starts to reciprocate against the drill bit, as will be described more fully hereinafter.

The valve is provided with an exhaust port groove 78^d, which is open to the atmosphere at one end and which is arranged to permit the air to exhaust from the feed tube 18 back through the ports 85, 84, 83, 82 and 81 and this groove 78^d to the atmosphere whenever it is desired to stop the rock drilling operation, which is done by moving the valve in the reverse direction from that in which it is turned to admit air, which movement first shuts off the air to the cylinder (see Fig. 20), and afterward shuts off the air to the feed tube, and then when the valve is further turned until its handle comes to its normal stop position (see Fig. 19), the port 78^d registers with the port 81, and the exhaust from the tube to the atmosphere is open and the drill is then inoperative.

Ports 58^a and 58^b respectively, are drilled in from opposite ends of the valve chest casing and parallel with the bore of said casing, as shown in Fig. 12, and their outer ends are plugged. These ports are intersected by horizontal ports 58^c and 58^d respectively, which are drilled through from the outside of the chest into its bore, these holes entering the chest a slight distance back of the inner ends of plugs 59, which inner ends are reduced in diameter, as shown in Fig. 1, to permit the entrance of air to the chest.

The inner ends of the ports 58^a and 58^b are intersected by vertical ports 58^e and 58^f respectively, which enter the hammer piston cylinder 5.

Air entering the rear end of the cylinder through inlet port 65 throws the hammer piston forward, and when its rear end uncovers the port 58^e, air passes through said port and through ports 58^a and 58^c to the rear end of the valve chest and throws the valve 58 to the forward end of the chest, as shown in Fig. 1, thereby opening port 66 and admitting air to the forward end of the cylinder, while at the same time the air behind the hammer piston exhausts through

the ports 65, 67 and 69. The hammer piston is now thrown to the rear and when its forward end uncovers the port 58^F, air is admitted to the chest in front of the valve 5 through the ports 58^F, 58^B and 58^D, and the valve is thrown to the rear end of the chest, thereby opening port 65 and permitting the air in front of the hammer piston to exhaust through ports 66, 68 and 69.

10 The end collars 61 and 62 of the slide valve are provided with small exhaust ports 61^A and 62^A, respectively. It will be noted that the distance between the port 58^F and the forward end of the cylinder is less than 15 the distance between the port 58^F and the rear end of the cylinder; this is in order that when the hammer piston has moved only a short distance on its rear stroke the said port 58^F will be opened and the slide valve 20 thrown to admit air to the rear of the hammer piston in time to cushion the piston on its rear stroke and thus prevent it from striking the rear cylinder head 14.

An oil reservoir 87 is formed upon the 25 bottom of the cylinder, the opposite ends of which are threaded to receive threaded plugs 88. Oil passages 89 and 90 are drilled in from opposite ends of the oil reservoir through the cylinder shell, and permit the 30 oil to work from the oil reservoir into the cylinder. This feature of my stoping drill is fully explained in Letters Patent No. 958,260, issued to me May 17, 1910.

The oil works from the reservoir to the 35 cylinder as the hammer piston reciprocates on the cylinder and wipes the oil up and distributes it throughout the cylinder, from which it works into the valve chest through its ports to the slide valve 58.

40 The operation of my improved air feeding device for stoping drills is as follows: The elbow 75 is connected to a hose, which I do not illustrate, but which extends to a supply of compressed air of from about 60 45 to 100 pounds pressure, which is admitted by the operator to the throttle valve which is rotated in its seat by its handle which is preferably arranged to engage a stop lug 79^A that is cast on the cylinder. The handle 50 stands in a horizontal position against this lug, as shown in Fig. 18, and is adapted to be moved upward and swing in a semi-circular path, and when all of the ports are open and the drill is being operated, the 55 handle is arranged to rest in a substantially horizontal position on the opposite side of the lug 79^A, as shown in Figs. 10 and 11, and this throttle valve admits air to the feed tube first, when moved to open the air 60 inlet ports and into the drill cylinder last, but the ports are so arranged that the valve keeps the air inlet ports to the feed tube constantly and continuously open from the time they are first opened until and during 65 the time the ports to the drill cylinder are

open and until they are closed by a reverse movement of the valve and the hammer piston stops running.

The operation and the detailed movement of the valve is as follows: The attendant 70 places the point of the abutment engaging piston rod against the floor or one of the side walls of the mine stope in which the drill is being used, or against any suitable abutment such as a block of wood, and then 75 grasps the handle of the valve, which, when the drill is not in use, has its exhaust port 78^D open to the atmosphere and stands as shown in Fig. 18. The operator having placed the abutment point of the piston rod 80 against an abutment in the stope of the mine, raises the handle from its horizontal position to a vertical position which turns the valve from its open feed tube exhaust position and closes the exhaust port from 85 the feed tube to the atmosphere and opens the port 78^C to the port 81 first, and allows the air to flow into the feed tube against the piston head and move the feed tube on the piston head forward, and the operator 90 guides the drill bit against the rock at the point where he desires to drill a hole, as the drill bit and the cylinder are moved forward with the tube by the air pressure on the piston head. The stoping drill is then 95 operatively set and supported between its abutment point and the point of the drill bit, and the hammer piston should then be started. This is done by moving the handle 100 from its vertical position down to a substantially horizontal position on the opposite side of the stop lug from which it started. This movement of the handle turns the valve to open its main port 78 to the air port 70 of the cylinder from which air flows 105 to the opposite end of the cylinder and reciprocates the hammer piston, which strikes the drill bit, and drills a hole in the rock while the operator oscillates the drill bit, cylinder and feed tube by swinging the 110 handle 48 in short reciprocal strokes. The air inlet port 78^B, however, still remains open from the time it is first opened when the handle is raised to a vertical position during its movement to open the port 70 to 115 admit air to the cylinder. As this port 78^B extends a quarter around the valve, it keeps the port 81 open to the feed tube and consequently air is admitted to the feed tube 120 constantly and continuously from the time the valve opens the feed tube port 81 until and during all the time the cylinder port is open. Consequently the operative movement of the handle and valve first closes the feed tube exhaust; second, opens the air 125 ports to the feed tube before air is admitted to the hammer piston cylinder; and third, then opens the air port to the hammer piston cylinder while continuously holding the air port to the feed port open, and thus 130

keeping the piston of the feed tube under constant pressure against its abutment and the drill bit against the rock. Upon wishing to stop the hammer piston and the drilling engine, the handle and the valve are reversed and the air is first shut off from the drill cylinder and then afterward from the feed tube, and then afterward the exhaust port is opened from the feed tube to the atmosphere. The complete operative cycle movement of the valve having then been made, the stoping drill is moved to a new position and the operation is repeated.

My invention provides a simple, thoroughly practical and highly efficient air feeding device for stoping drills, that is economical in the use of air, and one that is light and can be easily and quickly handled by a single operator when attached to an operative rock drilling cylinder such as is illustrated in my pending application, Serial No. 587,651, filed October 18, 1910.

Having described my invention, what I claim as new and desire to secure by Letters Patent is:

1. In a feeding device for stoping drills, the combination of the cylinder, its front cylinder head and drill holding cap and its rear sleeve and cylinder head portions and the air feed tube connected to said sleeve portion, said sleeve and air feed tube and cylinder and front cylinder head and cap portions being arranged in axial alinement and fitted to bear end to end together and provided on their opposite sides with laterally projecting lugs provided with bolt receiving apertures, recesses in the cap arranged and adapted to receive the heads of bolts and prevent them from turning, a spanner washer mounted loosely on said air feed tube and provided with bolt receiving apertures in alinement with the bolt receiving apertures of said cylinder and sleeve, bolts extending through all of said lugs and having their heads fitting in the said bolt head receiving recesses of said cap, expanding coiled springs mounted on said bolts between said spanner washer and the lugs of said sleeve, keyways across the outside surface of said spanner washer and arranged in a diametrical path across its bolt receiving apertures, and nuts threaded on the ends of said bolts and arranged to screw against the outer surface of said spanner washer and having their washer engaging ends provided with projecting keys arranged and adapted to fit into the keyways in the lugs of said sleeve whereby the resilient expansive tension of said springs locks said nuts to said spanner washer against accidental displacement and clampingly binds said sleeve and air feed tube and cylinder and cylinder head and cap together with a resiliently yielding pressure.

2. In a feeding device for stoping drills,

the combination of the cylinder and front and rear heads, the front cap, the air feed tube's supporting sleeve, the air feed tube and the spanner washer mounted slidably on said air feed tube with the bolts extending loosely through said cylinder and its heads, the front cap and the sleeve and the spanner washer, said spanner washer being provided with keyways extending across its rear surfaces in diametric alinement with the center of the bolts extending through it, nuts on the ends of said bolts provided with key portions adapted to fit into the keyways of said spanner washer and the expansive coiled springs mounted on said bolts between said spanner washer and said sleeve, whereby said cylinder parts are locked together with a resiliently clamping yielding pressure of any predetermined tension to stand the operation of drilling holes in rock.

3. A stoping drill, comprising an engine cylinder having a rear head, a feed piston, a tubular casing for the feed piston, and means connecting said cylinder and said casing for resiliently holding said casing against the rear cylinder head.

4. A stoping-drill comprising an engine having a rear cylinder head, a sleeve adjacent said rear cylinder head, a feed-piston, and a tubular casing for the feed-piston secured within the sleeve, and means for yieldingly clamping said tubular casing and said sleeve to said engine.

5. A stoping-drill comprising an engine, front and rear cylinder heads on said engine, a sleeve adjacent said rear cylinder head, a feeding mechanism comprising a feed-piston, a tubular casing for said feed-piston secured within said sleeve, and means for yieldingly clamping the feeding mechanism through said sleeve to the rear cylinder head.

6. A stoping-drill comprising an engine having a rear cylinder head provided with a shoulder, a feeding mechanism comprising a feed-piston, a tubular casing for the feed-piston fitting over said shoulder, a sleeve on said casing near the shoulder, a washer-plate on said tubular casing, and means between said sleeve and said washer plate for yieldingly clamping the feeding mechanism to said engine.

7. A stoping-drill comprising an engine having a rear cylinder head provided with a shoulder, a feed-piston, a tubular casing for the feed-piston fitting over said shoulder, a washer-plate on said tubular casing, drill-rocking means secured around the front end of said casing, and means comprising side-rods engaging the engine having coiled springs interposed between said washer-plate and said rocking means for yieldingly clamping the feeding mechanism to said engine.

8. A stoping-drill comprising an engine

having a front cylinder head and a rear cylinder head provided with a shoulder, a feed-piston, an outer sleeve adjacent said rear cylinder head having apertured flanges, a tubular casing for the feed-piston fitting over said shoulder and secured within said sleeve, drill-rocking means connected with said sleeve, a washer-plate on said tubular casing, and means comprising side-rods having coiled springs interposed between the

apertured flanges of said sleeve and said washer-plate for yieldingly clamping the feeding mechanism to the rear cylinder head.

In testimony whereof I affix my signature **15.**
in presence of two witnesses,

JOHN GEORGE LEYNER.
